UNITED STATES PATENT OFFICE.

FOREST V. DETWILER, OF CHICAGO, ILLINOIS.

REFRIGERATOR.

1,123,499.

Specification of Letters Patent.

Patented Jan. 5, 1915.

Application filed May 31, 1910. Serial No. 594,987.

To all whom it may concern:

Be it known that I, FOREST V. DETWILER, a citizen of the United States, residing in Chicago, in the county of Cook and State 5 of Illinois, have invented certain new and useful Improvements in Refrigerators, of which the following is a specification.

This invention relates to improvements in refrigerators and one of the objects of the 10 same is to provide a hollow cooling casing with which the city supply of water or ice may be used as a cooling medium and which casing is removably and centrally disposed within an inclosing casing whereby provision receptacles may be arranged on each 15 side thereof in such a manner that cold air discharged from the cooling casing will enter both of the provision receptacles to circulate therethrough.

20 A further object is to provide improved means for holding or retaining the cooling casing in position and improved means for supporting a screen to prevent the entrance of foreign matters into the cooling casing.

25 A further object is to provide improved means whereby the city supply of water may be discharged into the cooling casing and improved means whereby the casing may be readily drained.

30 A further object is to provide improved means whereby the provision receptacles may be detachably connected, and improved means whereby the provision receptacles may be readily removed from the inclosing 35 casing and independently with respect to the cooling casing.

35 A further object is to provide an improved structure of this character which will be simple, durable and cheap in construction and effective and efficient in operation.

To the attainment of these ends and the accomplishment of other new and useful objects, as will appear, the invention consists 45 in the features of novelty in the construction, combination and arrangement of the several parts hereinafter more fully described and claimed and shown in the accompanying drawings illustrating the embodiment of the invention, and in which—

Figure 1 is a vertical transverse sectional view of an improved refrigerator of this character constructed in accordance with the principles of this invention. Fig. 2 is 55 a front elevation of the outside of the casing showing the arrangement of the doors. Fig. 3

is a horizontal sectional view on line 3—3 of Fig. 1. Fig. 4 is a detail perspective view of one of the food provision receptacles. Fig. 5 is an enlarged detail view partly in elevation and partly in section showing the braces for supporting the walls of the cooling casing and for spacing the provision receptacle from the wall of the casing. Fig. 6 is a detail perspective view of a portion of the screen or guard for preventing the entrance of foreign matters into the cooling casing, and the support therefor. Fig. 7 is an enlarged detail sectional view showing the manner of supporting the supply pipes which discharge into the cooling casing when the city supply of water is used as a cooling medium. Fig. 8 is a view similar to Fig. 1 of another form of refrigerator. Fig. 9 is a front elevation of the casing of the refrigerator shown in Fig. 8 illustrating the arrangement of the doors of the refrigerator. Fig. 10 is a horizontal sectional view on line 10—10 of Fig. 8 showing the manner in which the provision receptacles on each side of the cooling casing may be connected. Fig. 11 is a detail perspective view of the form of cooling casing shown in Fig. 8. Fig. 12 is a perspective view of the connecting plate or member 85 between the provision receptacles shown in Fig. 13. Fig. 13 is a detail perspective view of the provision receptacles shown in Fig. 10 and the connecting member therefor, removed from the outer casing. 90

Referring more particularly to the drawings and in the present exemplification of the invention, the numeral 15 designates an inclosing casing having insulated walls and which may be of the ordinary and well known construction but in the present exemplification of the invention is shown as being of a rectangular construction. 95

Arranged within the inclosing casing and disposed centrally thereof is a hollow cooling casing which in the form of the invention shown in Figs. 1, 3 and 7 comprises an outer wall 16 and an inner wall 17, the walls 16 and 17 being spaced from each other and their ends being connected as at 18 to form 100 a tubular air passage surrounded by the cooling medium 19, which cooling medium is in the form of a liquid, preferably water. The cooling casing thus formed is also preferably of a rectangular construction and 105 may be of any desired height but is of a height to extend from the bottom of the in-

closing casing and terminate some distance from the top of the casing.

In order to strengthen or reinforce the walls 16, 17 of the cooling casing, braces 5 or spacing members 20 may be provided which may be of any desired construction and any number of which may be provided. These braces or spacing members are arranged within the cooling casing between 10 the walls 17 and the respective adjacent walls 16 and may be secured and held in position in any desired or suitable manner, preferably by means of one end thereof being reduced as at 21 and secured to one of 15 the walls of the cooling casing and the other end being reduced as at 22 to project through and beyond the other wall of the cooling casing. Attached to this extremity 22 of the member 20 is a cap 23 which is arranged adjacent the outer face of the respective wall 20 of the cooling casing and extends for a short distance beyond the face of the wall for spacers as hereinafter set forth.

Arranged within the inclosing casing 15 and above the cooling casing is a tray 24, which is of a configuration to conform to the interior of the inclosing casing. This tray 24 is provided with an inclined bottom, as shown, and the opposite edges are provided with 30 upwardly projecting flanges 25. The tray is formed with an elongated opening adjacent its center, preferably formed by cutting away a portion of the tray and bending the cut-away portion back upon itself as at 26, 35 shown more clearly in Fig. 6, and this portion 26 is spaced from the lower face of the bottom of the tray. The portion of the bottom adjacent the bent or deflected portion 26 is offset or depressed as at 27 for a purpose to be set forth.

The upper edges of the outer walls 16 of the cooling casing, in the form shown in Fig. 1 extend beyond the upper edges of the inner walls 17, and the edges of these walls 45 are deflected or bent outwardly as at 28, and then inwardly, as at 29, to form a lip or recess adapted to receive the deflected portion 26 of the bottom of the tray so that the cooling casing may be readily detached 50 from the tray and removed from the inclosing casing when the front thereof is detached and may as readily be replaced when desired.

The tray 24 may be supported within the 55 inclosing casing in any suitable manner, preferably by means of brackets 30 which are secured to the walls of the inclosing casing and the side edges of the tray terminate some distance short of the walls of 60 the inclosing casing. Uprights 31 are provided which are supported in any desired or suitable manner to form substantial continuations of the flanges 25 of the tray and these uprights 31 are also spaced from the 65 adjacent walls of the inclosing casing and

terminate short of the top thereof to form with the adjacent wall of the casing up-going air circulation passages and over the top of which uprights the air is discharged into the ice receiving chamber. A rack 33 70 is provided which extends across the tray 24 and is supported by the tray, and a platform or support 34 forms a portion of the rack and upon this platform or support 34 the ice 35 rests. This platform or support 34 75 preferably terminates some distance short of the uprights 31 to form passages for the down-going cold air from the ice chamber so that the cold air will pass under the platform or support 34 to be discharged into the 80 tubular passage formed by the walls 17, 18, of the cooling casing. The tubular passage formed by the walls 17 and 18 of the cooler open through the bottom of the cooler and the cooler may be supported by a suitable 85 rack or support 36 arranged in the bottom of the inclosing casing and in such a manner as to hold the bottom of the cooling casing or cooler above the bottom of the inclosing casing.

Arranged on each side of the cooling casing is a provision receptacle designated generally by the reference numeral 37 and which may be constructed of any suitable material, such as porcelain, metal or the like, and is 95 held spaced from the cooling casing by the caps 23. Shelves 38 are arranged within the provision receptacles and these shelves may be provided with the ordinary openings or perforations to permit the air to circulate 100 through the receptacles.

Each of the provision receptacles 37 is provided with one or more openings 39 adjacent the bottom thereof and the receptacles are so arranged that the walls which 105 are provided with the openings 39 will stand in proximity to the cooling casing, the openings 39 being preferably arranged below the bottom of the cooling casing. These provision receptacles are also each provided with 110 an opening 40 in the top thereof and these openings are preferably arranged adjacent the side wall of the provision receptacle opposite to that in which the openings 39 are arranged. When the provision receptacles 115 are arranged within the inclosing casing, the cap 23 of the spacing members 20 will hold the adjacent walls of the provision receptacles spaced from the cooling casing. An overflow pipe 41 is provided for controlling the height of the water 19 in the 120 cooling casing.

In the form of the invention as shown in Fig. 1, the cooling casing is supplied with the cooling medium or water from the ice 125 35. As the ice melts, the water will run down into the tray 24 and from the tray will be discharged into the cooling casing, the height thereof being controlled by the overflow pipe 41. In order to prevent the en- 130

trance of any foreign matter in the cooling casing, a guard preferably in the form of a screen 42, is provided and this screen is provided with a frame 43, a portion 44 of 5 which is bent or deflected upwardly as shown in Fig. 6 and the extremity of the portion 44 is bent or deflected laterally as at 45. When the guard or screen 42 is placed in position so as to extend across the 10 open top of the cooling casing and across the tubular passage formed by the walls 17 and 18 and also across the overflow pipe 36, the deflected portion 45 of the frame will rest in the recess or depressed portion 27 of 15 the tray, while the upright portions 44 of the frame will engage the edges of the elongated openings formed in the bottom of the tray to hold the guard or screen against displacement. A drip pan 46 is arranged in 20 the bottom of the inclosing casing to receive the water from the overflow pipe 36 and an outlet pipe 47 is connected with the drip pan by means of which the water may be discharged into the sewer pipe. It will be ap- 25 parent that the cold air from the ice will be discharged into the tubular passage formed by the walls 17 and 18 of the cooling casing and will be discharged through the bottom thereof to enter the provision receptacles 30 through the openings 39. It will then circulate upwardly in the direction of the arrows to pass out of the receptacles through the openings 40 and will enter the up-going air circulation passages 32 to be discharged 35 over the partitions or uprights 31 back into the ice chamber. As the water accumulates in the cooling casing it will overflow through the pipe 41 which latter may be provided with openings 48 provided for that purpose, 40 and will be discharged into the drip pan 46 to flow out of the pipe 47. A drain cock 49 is provided in the bottom of the cooling casing by means of which the latter may be readily drained of water when desired. The 45 front 50 of the inclosing casing is removably secured in position by means of suitable fastening devices 51 such as screws or the like, so that the entire front may be removed when it is desired to remove the provision 50 receptacles and also the cooling casing. The front is provided with closures 52 by means of which access may be had to the ice compartment and closures 53, one of which is provided for each of the provision receptacles. A supplemental door or closure 54 may be provided in the front 50 through which access may be had to the drain cock 49.

When it is desired to use the city supply 60 of water as a cooling medium, one or more pipes 55 (shown more clearly in Fig. 7) may be provided and these pipes are preferably provided with nozzles 56 and are supported by means of suitable brackets 57 65 which preferably removably engage over

the top edges of the walls 17 so that the pipes may be removably supported in position. The nozzles 56 are preferably arranged so that water discharged therefrom will be directed against the outer face of the 70 walls 17 and into the cooling casing. The pipes 55 receive their supply by means of a suitable supply pipe 58 which extends through one of the walls of the casing.

In the form of the invention shown in 75 Figs. 8 to 13, the cooling casing comprises a hollow base 59, projecting from and communicating with which are a plurality of spaced tubular members 60. These tubular members 60 may be of any desired height 80 and supported thereby and communicating therewith is a tank 60 which is open at the top. Arranged within each of the tubular members 60 is an air pipe or tube 62, one end of which has communication with the 85 air in the inclosing casing through the bottom of the hollow base 59 as shown in Fig. 8. The other end of these pipes 62 project for some distance above the bottom of the tank 61. These pipes 62 are of a diameter 90 somewhat smaller than the interior diameter of the tubular members 60 so that when the cooling casing or cooler is filled with water, the air pipes 62 will be completely surrounded by water, as shown in Fig. 8. An 95 overflow pipe 63 similar to the overflow pipe 41 is provided and a drain cock 64, similar to the drain cock 49, is provided. The tray 65 is provided with an inclined bottom and an opening at the center thereof surrounded 100 by a depending flange 66 and this flange 66 projects into the tank 61 for a short distance so as to direct the water from the ice into the casing. A rack 67 and a support 68 similar to the rack and support 33, 34, are 105 also provided and upon which the ice rests. A circumferential flange 69 is provided on the tray 65 and uprights or partitions 70 are arranged to surround the flange to form up-going air circulation passages 71 similar 110 to the passages 32 and brackets 72 are also provided for supporting the tray and the uprights. Brackets 73 are provided within the flange 66 and a guard or screen 74 is supported by these brackets 73 to prevent 115 the entrance of foreign matter into the cooling casing or cooler. Provision receptacles 75 are provided on each side of the cooling casing and the walls 76 thereof engage and rest against the side of the tank 61 and the 120 side of the hollow base 59. These walls 76 are provided with openings 77 similar to the openings 39 through which the cold air discharged from the cooler enters the food receptacles. Openings 78 similar to the openings 40 are also provided to permit the up-going warm air to be discharged from the provision receptacles. In this form of the invention the provision receptacles 75 are 125 preferably constructed of metal and the 130

front edges of the walls 76 are bent or deflected back upon themselves to form lips 79 spaced from the adjacent faces of the walls 76 to form grooves opening outwardly. A connecting member 80 preferably in the form of metal is provided with spaced parallel flanges 81 extending substantially the entire length thereof. This member 80 is of a width equal to the space 10 between the walls 76 and the flanges 81 thereof are adapted to enter the groove formed by the lips 79 to connect the provision receptacles and also to form a shield or protector, extending across the end of the 15 cooling casing and also to form a closure for the space between the receptacles. This member 80 is provided with openings 83 by means of which it may be readily detached. In this form of the invention, the front 84 20 of the casing is provided with an opening closed by a single closure 85 and this opening is of such a size that when opened, the provision receptacles may be readily and bodily removed from the inclosing casing 25 as well as the cooling casing or cooler. When it is desired to remove either the provision receptacles or the cooling casing the member 80 is first detached and either the provision receptacles or the cooling casing, 30 or both, may be removed from the inclosing casing at will. The front 84 of the refrigerator is also provided with closures 86 inclosing openings through which access may be had to the ice compartment. In this form 35 of the invention when it is desired to drain the cooling casing, the closure 85 is first opened and the member 80 then removed which may be readily accomplished, after which access may be had to the cock 77. 40 When it is desired to use the city supply of water as the cooling medium, the water is supplied to the cooling casing, through the pipe 87 which extends through one of the walls of the casing and rests upon the 45 bottom of the tank 61 so as to discharge into the tubular members 60.

If desired, spacing members 88 may be provided which engage the walls 76 and serve to hold the food receptacles 75 in 50 position.

In order to reinforce the edges of the various metallic parts, the extremities of the edges may be deflected or bent back upon themselves in a manner similar to that 55 shown at 89 in Fig. 7.

What is claimed as new is—

1. In a refrigerator, the combination of an inclosing casing, a removable hollow cooler therein dividing said casing into two 60 compartments, said cooler having a source of supply of cooling liquid, provision receptacles in the compartments on each side of and independent of the cooler, said receptacles extending below the bottom of the 65 cooler, and an air circulation passage

through the cooler, one end of which discharges through the bottom of the cooler, the walls of the provision receptacles adjacent the cooler being provided with openings below the cooler through which the air discharged from the air passage will enter the receptacles to circulate therethrough. 70

2. In a refrigerator, the combination of an inclosing casing, a removable hollow cooler therein dividing said casing into two 75 compartments, said cooler having a source of supply of cooling liquid, provision receptacles in the compartments on each side of and independent of the cooler, said receptacles extending below the bottom of the 80 cooler, an air circulation passage through the cooler, one end of which discharges through the bottom of the cooler, the walls of the provision receptacles adjacent the cooler being provided with openings below the 85 cooler through which the air discharged from the air passage will enter the receptacles to circulate therethrough, a drain opening for the cooler, and a stop cock within the inclosing casing and disposed in 90 the space between the provision receptacles for controlling the drain opening. 95

3. In a refrigerator, the combination of an inclosing casing, a removable hollow cooler therein dividing said casing into two compartments, said cooler having a source of supply of cooling liquid, provision receptacles in the compartments on each side of and independent of the cooler, a drain opening for the cooler, a stop cock within the inclosing 100 casing and disposed in the space between the provision receptacles for controlling the opening, and means whereby access may be had to the stop cock through the wall of the inclosing casing. 105

4. In a refrigerator, the combination of an inclosing casing, a hollow cooler having an open top and adapted to receive a cooling liquid, a drip receptacle within the casing and supported above the cooler, said receptacle discharging into the cooler, an air circulation passage extending through the 110 cooler and surrounded by the liquid, a screen extending across the cooler and through which the liquid passes into the cooler and provision receptacles below the drip receptacle and disposed on each side of the cooler 115 with one wall adjacent the cooler. 120

5. In a refrigerator, the combination of an inclosing casing, a hollow cooler having an open top and adapted to receive a cooling liquid, a drip receptacle within the casing and supported above the cooler, said receptacle discharging into the cooler, interengaging means on the receptacle and cooler 125 for detachably securing the two together, an air circulation passage extending through the cooler and surrounded by the liquid, a screen extending across the cooler and through which the liquid passes into the re- 130

- ceptacle and provision receptacles below the drip receptacle and disposed on each side of the cooler with one wall adjacent the cooler.
5. In a refrigerator, the combination of an inclosing casing, a hollow cooler centrally disposed within the casing and dividing it into separate compartments, means for supporting the bottom of the cooler above the base of the casing, said cooler having a source of supply of cooling liquid, provision receptacles on each side of the cooler and having openings in their walls through which the air from the cooler passes, a drain cock for the cooler leading from the bottom and entirely within the casing, one of the walls of the casing having an opening through which access may be had to the stop cock and a closure for the opening.
10. 7. In a refrigerator, the combination of an inclosing casing, a hollow cooler centrally disposed therein and having a source of supply of cooling fluid, provision receptacles arranged on each side of the cooler, a drain for the cooler embodying a stop cock leading from the bottom thereof, the walls of the receptacles being provided with openings adjacent the cooler, and means separate from the wall of the casing forming a closure for the space between the receptacles and extending thereacross for inclosing the cooler.
15. 8. In a refrigerator, the combination of an inclosing casing, a hollow cooler centrally disposed therein and having a source of supply of cooling fluid, provision receptacles arranged on each side of the cooler, a drain for the cooler embodying a stop cock leading from the bottom thereof, the walls of the receptacles being provided with openings adjacent the cooler, and means separate from the walls of the casing removably secured in position to form a closure for the space between the receptacles and extending thereacross for inclosing the cooler.
20. 9. In a refrigerator, the combination of an inclosing casing, a hollow cooler centrally disposed therein and having a source of supply of cooling fluid, provision receptacles independent of and arranged on each side of the cooler, and a closure for the space between the receptacles detachably connected with adjacent walls of the receptacles.
25. 10. In a refrigerator, the combination of an inclosing casing, a hollow cooler centrally disposed therein and having a source of supply of cooling fluid, provision receptacles independent of and arranged on each side of the cooler, a closure for the space between the receptacles detachably connected with adjacent walls of the receptacles, an air circulation passage extending through the cooler, and means whereby the air discharged from the cooler will enter the provision receptacles.
30. 11. In a refrigerator, the combination of an inclosing casing, a hollow cooler centrally disposed therein and having a source of supply of cooling fluid, an air circulation passage through the cooler, provision receptacles on opposite sides of the cooler, means whereby the air discharged through the cooler will enter the receptacles, portions of adjacent walls of the receptacles being shaped to form fastenings and a member detachably engaging the fastenings and extending across the space between the receptacles and in front of the end of the cooler.
35. 12. In a refrigerator, the combination of an inclosing casing, a hollow cooler centrally disposed therein and having a source of supply of cooling fluid, an air circulation passage through the cooler, provision receptacles on opposite sides of the cooler, means whereby the air discharged through the cooler will enter the receptacles, portions of adjacent walls of the receptacles being shaped to form grooves extending lengthwise of the edges of the walls, and a member extending across the space between the receptacles to form a closure therefor, said member being provided with portions adapted to removably enter the grooves.
40. 13. In a refrigerator, the combination of an inclosing casing, a hollow cooler centrally disposed therein and having a source of supply of cooling fluid, an air circulation passage through the cooler, provision receptacles on opposite sides of the cooler, means whereby the air discharged through the cooler will enter the receptacles, portions of adjacent walls of the receptacles being shaped to form grooves extending lengthwise of the edges of the walls, a member extending across the space between the receptacles to form a closure therefor, said member being provided with portions adapted to removably enter the grooves and being removable through the front of the inclosing casing.
45. 14. In a refrigerator, the combination of an inclosing casing, a hollow cooler open at the top and arranged centrally therein, provision receptacles on opposite sides of the cooler, a drip receptacle provided with an opening in its bottom and having its bottom inclined toward said opening, a flange adjacent the opening, said flange having engagement with the open top of the cooler to discharge the water therein, an air circulation opening passing through the cooler, and a screen removably supported by the receptacle and extending across the cooler.
50. 15. In a refrigerator, the combination of an inclosing casing, a hollow cooler open at the top and arranged centrally therein, provision receptacles on opposite sides of the cooler, a drip receptacle provided with an opening in its bottom and having its

bottom inclined toward said opening, interengaging means on the drip receptacle adjacent the said opening and on the wall of the cooler for detachably securing the two 5 together, a screen for the cooler, and an air circulation passage through the cooler.

16. In a refrigerator, the combination of an inclosing casing, a hollow cooler open at the top and arranged centrally therein, 10 provision receptacles on opposite sides of the cooler, a drip receptacle having an opening in its bottom, and flanges on opposite sides of the opening and extending below the receptacle, said flanges being bent back 15 upon themselves to form lips, the edges of the walls of the cooler adjacent said flanges being shaped to form lips adapted to engage with the first said lips for detachably securing the drip receptacle and cooler together, 20

17. In a refrigerator, the combination of an inclosing casing, a hollow cooler open at the top and arranged centrally therein, provision receptacles on opposite sides of 25 the cooler, a drip receptacle having an opening in its bottom, flanges on opposite sides of the opening and extending below the receptacle, said flanges being bent back upon themselves to form lips, the edges of the 30 walls of the cooler adjacent said flanges being shaped to form lips adapted to engage with the first said lips for detachably securing the drip receptacle and cooler together, and a screen removably supported 35 by the walls of the opening in the drip receptacle and extending across said opening.

18. In a refrigerator, the combination of an inclosing casing, a hollow cooler open at the top and arranged centrally therein, provision 40 receptacles on opposite sides of the cooler, a drip receptacle having an opening in its bottom, flanges on opposite sides of the opening and extending below the receptacle, said flanges being bent back upon 45 themselves to form lips, the edges of the walls of the cooler adjacent said flanges being shaped to form lips adapted to engage with the first said lips for detachably securing the drip receptacle and cooler together, 50 a screen removably supported by the walls of the opening in the drip receptacle and extending across said opening, portions of the bottom of the drip receptacle being depressed or offset to form recesses into 55 which opposite edges of the screen are seated.

19. In a refrigerator, the combination of an inclosing casing, a hollow cooler therein, means for supplying the cooler with a cooling liquid embodying a supply pipe provided with outlets discharging into the cooler, and means for supporting the pipe, said means having detachable engagement with the cooler, 60

65 20. In a refrigerator, the combination of

an inclosing casing, a hollow cooler therein, means for supplying the cooler with a cooling liquid embodying a supply pipe provided with outlets discharging into the cooler, and suspended means for supporting the pipe, said means having detachable engagement with the cooler. 70

21. In a refrigerator, the combination of an inclosing casing, a hollow cooler therein, means for supplying the cooler with a cooling liquid embodying a supply pipe provided with outlets discharging into the cooler, and brackets for supporting the pipe, said brackets detachably engaging over the edge of the cooler. 75

22. In a refrigerator, the combination of an inclosing casing, a hollow cooler therein, means for supplying the cooler with a cooling liquid embodying a supply pipe, a nozzle leading from the pipe, and means for supporting the pipe, said nozzle being disposed to discharge the liquid directly against the wall of the cooler. 80

23. In a refrigerator, the combination of an inclosing casing, a hollow cooler therein comprising a tube forming the inner wall, means for supplying the cooler with a cooling liquid embodying a supply pipe, a nozzle leading from the pipe, brackets detachably engaging over the wall of the tube for 90 removably supporting the pipe, and a discharge nozzle for the pipe, said nozzle being disposed to discharge the liquid directly against the inner wall of the cooler. 95

24. In a refrigerator, the combination of an inclosing casing, a hollow cooler therein, an air circulation tube within the cooler spaced from the walls thereof forming the inner wall of the cooler and surrounded by the cooling liquid, means for supplying the 100 cooler with a cooling liquid embodying a pipe provided with one or more discharge nozzles, and a bracket for removably supporting the pipe, said bracket detachably engaging over the edge of one of the walls 105 of the cooler. 110

25. In a refrigerator, the combination of an inclosing casing, a hollow cooler therein, an air circulation tube within the cooler spaced from the walls thereof forming the 115 inner wall of the cooler and surrounded by the cooling liquid, means for supplying the cooler with a cooling liquid embodying a pipe provided with one or more discharge nozzles, and a bracket for removably supporting the pipe, said bracket detachably engaging over the edge of one of the walls of the cooler, said nozzles being disposed to discharge the liquid directly against the side wall of the cooler. 120

26. In a refrigerator, the combination of an inclosing casing, a hollow cooler therein, an air circulation tube within the cooler spaced from the walls thereof forming an inner wall of the cooler and surrounded by 130

the cooling liquid, means for supplying the cooler with a cooling liquid embodying a pipe provided with one or more discharge nozzles, and a bracket for removably supporting the pipe, said bracket detachably engaging over the edge of the air tube, said nozzles being inclined toward the face of the air tube to discharge the liquid directly against the said face of the tube.

In testimony whereof I have signed my name to this specification, in the presence of two subscribing witnesses, on this 25th day of May A. D. 1910.

FOREST V. DETWILER.
